Section 1, Public Law 690, August 8, 1946
Patent expires July 27, 1959

13 Claims. (Cl. 200—148)

1

This invention relates to pneumatic circuit breakers, and more particularly to those provided with an auxiliary electrode in the path of the arc.

One of the objects of the present invention is to provide such a circuit breaker in which the auxiliary electrode is located in a blow-out chamber having two opposed nozzles and has its ends located axially of said nozzles.

The present invention and its various aims and objects will be readily understood from the following description, taken in connection with the accompanying drawing, showing one embodiment of the invention herein given for illustrative purposes, the true scope of the present invention being more particularly pointed out in the appended claims.

In the drawing:

Fig. 1 shows, partly in elevation and partly in section, one embodiment of the invention during the first stage of its operation;

Fig. 2 is similar to Fig. 1 but shows the parts during another stage of the operation;

Fig. 3 is a cross-section of the embodiment shown in Figs. 1 and 2 and illustrating more particularly the relatively movable arc-drawing contacts 1 and 2 and the auxiliary contact 4, on a somewhat enlarged scale.

In the embodiment of the invention shown, the circuit breaker comprises two relatively movable arc-drawing contacts 1 and 2, the former being fixed and the other movable, and an auxiliary contact 4 which is fixed and located in the axis of this movable contact, the latter being tubular to receive this auxiliary contact and being provided with a longitudinal slot 3 for the passage of the stem of the auxiliary contact to enable the movable contact 2 to effect its stroke. The blow-out chamber is shown at 5 and is provided in two opposite walls with two opposed nozzles 6 and 7 through which the movable contact 2 effects its stroke. The blow-out chamber 5, as shown, including its opposite walls provided with nozzles, is preferably formed of some suitable refractory electrical insulating material, or, in any event, its opposite walls having the nozzles are electrically isolated from all current carrying parts of the apparatus. One of the lateral walls of the chamber, other than the opposite walls provided with nozzles, is provided with an aperture tightly receiving and mounting the mounting stem of auxiliary electrode 4. This auxiliary contact is aligned with the axis of said two nozzles 6 and 7, the inner surfaces of which are divergent-convergent, the bores being wider

2

at their end portions than at their center portions. As shown, the auxiliary contact 4 is elongated and its ends extend into the nozzles 6 and 7. The nozzles 6 and 7 are venturi nozzles having restricted throats and, as shown, the ends of auxiliary contact 4 preferably terminate respectively at these restricted throats. A resistance 8 is connected on the one hand to the fixed contact 1 and on the other hand to the auxiliary electrode 4. The fluid or gas for the blast is supplied to the blow-out chamber 5 through a passage 9 opening into the space separating the nozzles 6 and 7, and substantially at right angles to the axis of the latter. The walls of this passage 9 may support said blow-out chamber.

The operation is as follows. As the movable contact 2 is retracted, an arc is struck between it and the fixed contact 1 and is drawn out. As soon as the arc thus drawn reaches the level 20 of the upper part of the auxiliary electrode 4, it attaches itself to the latter. The part of said arc extending between said auxiliary electrode 4 and the fixed contact 1 will thus be shunted by the resistance 8 and blown with great force 25 by the blast fluid blown out through said nozzle 6. This arc being thus extinguished, the resistance 8 is thrown into the circuit. The movable contact 2 continuing its stroke, a second arc will be struck between the lower portion of 30 the auxiliary contact 4 and the movable contact 2, but the strength of the current having been greatly diminished by the throwing into the circuit of the resistance 8, this second arc will be readily extinguished by the blast fluid or gas blown out through said nozzle 7.

Movement of the movable contact 2 may be effected by any suitable mechanism of conventional construction heretofore used in circuit breakers.

The fixed contact 1 may, and preferably will be, mounted so as to cushion the impact of contact 2 upon contact 1, this mounting herein comprising relatively sliding telescoping sleeves 11, 12 and interposing spring 13, as illustrated in Fig. 3, which shows upon an enlarged scale the relative positions of the contacts 1 and 2, the auxiliary electrode 4 and the nozzles 6 and 7.

It will be apparent that the relative mobility of the arc-drawing contacts could be realized by making both contacts movable, one after the other for example, and that capacity means could be substituted for the resistance, or inductive means could be substituted, or such al-

ternative means could be connected in parallel with the resistance.

Circuit breakers embodying the present invention possess many advantages over those heretofore used, more particularly as regards the perfect safety with which the resistance is inserted in the circuit of the arc, and the severance of the second arc in series with said resistance; this safety is assured by the perfect separation of the two arcs and by the fact that each of the arcs is blown out by an appropriate nozzle. Furthermore, no part of the arc enters the pressure chamber, thus avoiding great constraint of the arc and the creation of excessive voltages at the moment of the rupture of the arc. In addition, the blow-out fluid or gas is used to better advantage as the arc does not affect it and does not impede its exhaust.

I am aware that the present invention may be embodied in other specific forms without departing from the spirit or essential attributes thereof, and I therefore desire that the present embodiment of the invention be considered in all respects as illustrative and not restrictive, reference being had to the appended claims rather than to the foregoing description to indicate the scope of the invention.

I claim:

1. In a circuit breaker with pneumatic blow-out, a principal fixed electrode, a movable elongated electrode having a contact end, means for moving said movable electrode and its contact end axially thereof away from and toward said fixed electrode, a closed blow-out chamber having two spaced opposite walls which are electrically insulating, said chamber being interposed in the path of the contact end of said movable electrode between the extreme closed and open positions thereof, said chamber being provided with two nozzle openings respectively in said opposite walls thereof and aligned axially in the path of said movable electrode therethrough and providing a clearance around said movable electrode, and a separate auxiliary electrode fixedly carried by said chamber in a position intermediate and extending between and spaced from said opposite walls thereof and close to but spaced from said movable electrode during its passage through said chamber, said movable electrode and auxiliary electrode being so constructed as to permit the movement of said movable electrode past said auxiliary electrode with narrow clearance therefrom.

2. In a circuit breaker with pneumatic blow-out, a principal fixed electrode, a movable elongated electrode having a contact end, means for moving said movable electrode and its contact end axially thereof away from and toward said fixed electrode, a closed blow-out chamber having two spaced opposite walls which are electrically insulating, said chamber being interposed in the path of the contact end of said movable electrode between the extreme closed and open positions thereof, said chamber being provided with two nozzle openings respectively in said opposite walls thereof and aligned axially in the path of said movable electrode therethrough and providing a clearance around said movable electrode, and a separate auxiliary electrode fixedly carried by said chamber in a position intermediate and extending between and spaced from said opposite walls thereof and with portions thereof extending substantially to each of said nozzle openings and being close to but spaced from said movable electrode during

its passage through said chamber, said movable electrode and auxiliary electrode being so constructed as to permit the movement of said movable electrode past said auxiliary electrode with narrow clearance therefrom.

3. In a circuit breaker with pneumatic blow-out, a principal fixed electrode, a movable elongated electrode having a contact end, means for moving said movable electrode and its contact end axially thereof away from and toward said fixed electrode, a closed blow-out chamber having two spaced opposite walls which are electrically insulating, said chamber being interposed in the path of the contact end of said movable electrode between the extreme closed and open positions thereof, said chamber being provided with two nozzle openings respectively in said opposite walls thereof and aligned axially in the path of said movable electrode therethrough and providing a clearance around said movable electrode, said movable electrode being tubular, and a separate elongated rod-shaped auxiliary electrode fixedly carried by said chamber in a position within the bore of said tubular movable electrode and in close clearance therewith during the passage of said movable electrode through said chamber.

4. In a circuit breaker with pneumatic blow-out, a principal fixed electrode, a movable elongated electrode having a contact end, means for moving said movable electrode and its contact end axially thereof away from and toward said fixed electrode, a closed blow-out chamber having two spaced opposite walls which are electrically insulating, said chamber being interposed in the path of the contact end of said movable electrode between the extreme closed and open positions thereof, said chamber being provided with two nozzle openings respectively in said opposite walls thereof and aligned axially in the path of said movable electrode therethrough and providing a clearance around said movable electrode, said movable electrode being tubular, and a separate elongated rod-shaped auxiliary electrode fixedly carried by said chamber in a position within the bore of said tubular movable electrode and in close clearance therewith during the passage of said movable electrode through said chamber, said auxiliary electrode having terminal portions thereof extending to each of said nozzle openings.

5. In a circuit breaker with pneumatic blow-out, a principal fixed electrode, a movable elongated electrode having a contact end, means for moving said movable electrode and its contact end axially thereof away from and toward said fixed electrode, a closed blow-out chamber having two spaced opposite walls which are electrically insulating, said chamber being interposed in the path of the contact end of said movable electrode between the extreme closed and open positions thereof, said chamber being provided with two nozzle openings respectively in said opposite walls thereof and aligned axially in the path of said movable electrode therethrough and providing a clearance around said movable electrode, said movable electrode being tubular, a separate elongated rod-shaped auxiliary electrode, mounting means carried by said chamber and carrying said auxiliary electrode for fixedly mounting said auxiliary electrode in said chamber in a position intermediate and extending between and spaced from said opposite walls thereof and for mounting said auxiliary electrode within the bore of said tubular mov-

able electrode and in close clearance therewith during the passage of said movable electrode through said chamber, said tubular movable electrode comprising means for permitting the passage therethrough of said mounting means as said movable electrode moves through said chamber.

6. In a circuit breaker with pneumatic blow-out, a principal fixed electrode, a movable elongated electrode having a contact end, means for moving said movable electrode and its contact end axially thereof away from and toward said fixed electrode, a closed blow-out chamber having two spaced opposite walls which are electrically insulating, said chamber being interposed in the path of the contact end of said movable electrode between the extreme closed and open positions thereof, said chamber being provided with two nozzle openings respectively in said opposite walls thereof and aligned axially in the path of said movable electrode therethrough and providing a clearance around said movable electrode, said movable electrode being tubular, a separate elongated rod-shaped auxiliary electrode, mounting means carried by said chamber and carrying said auxiliary electrode for fixedly mounting said auxiliary electrode in said chamber in a position intermediate and extending between and spaced from said opposite walls thereof and for mounting said auxiliary electrode within the bore of said tubular movable electrode and in close clearance therewith during the passage of said movable electrode through said chamber, said tubular movable electrode comprising means for permitting the passage therethrough of said mounting means as said movable electrode moves through said chamber, said auxiliary electrode having terminal portions thereof extending substantially to each of said nozzle openings.

7. In a circuit breaker with pneumatic blow-out, a principal fixed electrode, a movable elongated electrode having a contact end, means for moving said movable electrode and its contact end axially thereof away from and toward said fixed electrode, a closed blow-out chamber having two spaced opposite walls which are electrically insulating, said chamber being interposed in the path of the contact end of said movable electrode between the extreme closed and open positions thereof, said chamber being provided with two nozzle openings respectively in said opposite walls thereof and aligned axially in the path of said movable electrode therethrough and providing a clearance around said movable electrode, said movable electrode being tubular, a separate elongated rod-shaped auxiliary electrode, mounting means carried by said chamber and carrying said auxiliary electrode for fixedly mounting said auxiliary electrode therein and for mounting said auxiliary electrode in said chamber in a position intermediate and extending between and spaced from said opposite wall thereof and within the bore of said tubular movable electrode and in close clearance therewith during the passage of said movable electrode through said chamber, said tubular movable electrode comprising means for permitting the passage therethrough of said mounting means as said movable electrode moves through said chamber, and means for supplying gas under pressure to said chamber.

8. A circuit breaker according to claim 5, said nozzle openings being coaxial Venturi nozzles,

and said auxiliary electrode being substantially coaxial with said nozzle openings.

9. A circuit breaker according to claim 5, and an impedance connected between said auxiliary electrode and said principal fixed electrode.

10. A circuit breaker according to claim 5, and a resistance connected between said auxiliary electrode and said principal fixed electrode.

11. In a circuit breaker with pneumatic blow-out, a principal fixed electrode, a movable elongated electrode having a contact end, means for moving said movable electrode and its contact end axially thereof away from and toward said fixed electrode, a closed blow-out chamber interposed in the path of the contact end of said movable electrode between the extreme closed and open positions thereof, said chamber being provided with two nozzle openings respectively in opposite walls thereof and aligned axially in the path of said movable electrode therethrough and providing a clearance around said movable electrode, said movable electrode being tubular, and a separate elongated rod-shaped auxiliary fixedly carried by said chamber in a position within the bore of said tubular movable electrode and in close clearance therewith during the passage of said movable electrode through said chamber, and gas inlet means mounted in the lateral wall of said chamber connecting said opposite walls thereof, and adapted to deliver into said chamber a blast of gas under pressure in a direction substantially perpendicular to the axis of said nozzles and to the path of said movable electrode through said chamber.

12. In a circuit breaker with pneumatic blow-out, a principal fixed electrode, a movable elongated electrode having a contact end, means for moving said movable electrode and its contact end axially thereof away from and toward said fixed electrode, a closed blow-out chamber interposed in the path of the contact end of said movable electrode between the extreme closed and open positions thereof, said chamber being provided with two nozzle openings respectively in opposite walls thereof and aligned axially in the path of said movable electrode therethrough and providing a clearance around said movable electrode, said movable electrode being tubular, a separate elongated rod-shaped auxiliary electrode, mounting means carried by said chamber for fixedly mounting said auxiliary electrode therein and for mounting said auxiliary electrode within the bore of said tubular movable electrode and in close clearance therewith during the passage of said movable electrode through said chamber, said tubular movable electrode comprising means for permitting the passage therethrough of said mounting means as said movable electrode moves through said chamber, and gas inlet means mounted in the lateral wall of said chamber connecting said opposite walls thereof, and adapted to deliver into said chamber a blast of gas under pressure in a direction substantially perpendicular to the axis of said nozzles and to the path of said movable electrode through said chamber.

13. In a circuit breaker with pneumatic blow-out, a principal fixed electrode, a movable elongated electrode having a contact end, means for moving said movable electrode and its contact end axially thereof away from and toward said fixed electrode, a closed blow-out chamber having two spaced opposite walls, said chamber being provided in said opposite walls thereof

with coaxial venturi nozzle openings each having a restricted throat and aligned axially in the path of said movable electrode therethrough and providing a clearance around said movable electrode, said movable electrode being tubular, a separate elongated rod-shaped auxiliary electrode, mounting means carried by said chamber and carrying said auxiliary electrode for fixedly mounting said auxiliary electrode in said chamber in a position intermediate and extending between and spaced from said opposite walls thereof and for mounting said auxiliary electrode within the bore of said tubular movable electrode and in close clearance therewith during the passage of said movable electrode through said chamber and substantially coaxial with said nozzle openings, said tubular movable electrode comprising means for permitting the passage therethrough of said mounting means as said movable electrode moves through said chamber, 20 said auxiliary electrode having terminal portions thereof which extend into said venturi nozzle

openings and respectively terminate substantially at the restricted throats thereof.

BERNARD MARIE HILAIRE PAUL FERNIER.
